B. M. HAMLIN.
DRAWER LOCKING DEVICE.
APPLICATION FILED OCT 25, 1920.

1,379,977.

Patented May 31, 1921.

UNITED STATES PATENT OFFICE.

BEN M. HAMLIN, OF CHICAGO, ILLINOIS, ASSIGNOR TO J. V. MEYERING TRUNK COMPANY, OF CHICAGO, ILLINOIS, A CORPORATION OF ILLINOIS.

DRAWER-LOCKING DEVICE.

1,379,977.

Specification of Letters Patent. Patented May 31, 1921.

Application filed October 25, 1920. Serial No. 419,308.

To all whom it may concern:

Be it known that I, BEN M. HAMLIN, a citizen of the United States, and a resident of Chicago, Cook county, and State of Illinois, have invented certain new and useful Improvements in Drawer-Locking Devices, of which the following is declared to be a full, clear, and exact description.

This invention relates to drawer locking devices and in the present instance it has been illustrated as applied to the drawers of wardrobe trunks, although it is to be understood that my invention is not to be limited thereto.

15 The principal object of the present invention is to provide means for locking a tier of drawers, controlled by one of the drawers, whereby when said controlling drawer is locked, all of the others will be secured 20 against withdrawal and when the controlling drawer is unlocked, all of the others will be free to be opened.

This invention contemplates the use of strips extending parallel with a tier of 25 drawers at places adjacent their side edges and capable of overlapping the drawers so as to permit their withdrawal, and one of the objects of this invention is to dispense with separate locking means, other than 30 that of one drawer, for holding said strips in locking engagement with the drawers. Another object is to simplify, cheapen and otherwise improve on drawer locking devices of this character, and with all of said objects 35 in view, this invention consists in the several novel features hereinafter fully set forth and claimed.

This invention is clearly illustrated in the accompanying drawing, in which:—

40 Figure 1 is a front elevation of the drawer section and a fragment of the garment section of a wardrobe trunk, showing a simple embodiment of the present invention applied thereto; Fig. 2 is a detail, horizontal, fragmental section taken on line 2—2 of Fig. 1; Fig. 3 is a view similar to Fig. 2, but showing the drawer partly open; Fig. 4 is a front elevation of one of the upper corners of the drawer section and Fig. 5 is a detail, vertical section taken on line 5—5 of Fig. 4.

45 Referring to said drawing; which illustrates a simple embodiment of the invention applied to the drawer section of a wardrobe trunk the reference character 10 designates

the drawer section and 11 a fragment of the wardrobe section of a wardrobe trunk of ordinary construction, these parts being hinged together along a vertical line and having locking means (not shown) for securing them together as is usual. The drawer section 10 comprises a box-like casing 12, in which is supported a tier of drawers 15, 16, by partitions, strips or cleats 14 secured to the sides of the casing as is customary. Handles on the front walls of the drawers are provided to facilitate their withdrawal. The ordinary valance 17 is secured along the edge portion of the casing as is customary.

Extending along the front edges of the two side walls 18 of the casing 12 are two drawer retaining members 19, preferably made of thin flat metal strips, and said strips are each of sufficient length to extend along the entire tier of drawers. Said strips may be secured to the side walls 18 of the casing 12 by hinges 20 arranged along their length, so that they may be swung over the side edge portions of the drawers, as shown in Figs. 1 and 2, to thereby prevent withdrawal of the drawers, and they may be swung away from the drawers, as shown in Fig. 3, whereby the drawers are free to be withdrawn or pushed back into the casing.

For holding both of said strips 19 in locking engagement with said drawers, one of the drawers, for instance the uppermost one, has projecting members 21, 21, that are arranged to engage over the strips 19, when said upper drawer is fully closed, to thereby hold the strips in locking engagement with the remaining drawers. Said projecting member 21 may comprise short strips secured to the front face of the drawer 15 and having parts that project beyond the ends thereof, in position to engage over the drawer retaining strips 19, when said drawer 15 is fully closed. In this instance the lock controlled drawer 15 is made narrower than the drawers 16.

The drawer 15 is the controlling drawer, that is to say, it is the one that locks or unlocks the other drawers of the tier. A key lock 22 is secured to said drawer 15 and its bolt 23 engages with a keeper 24 secured to the underside of the top member 25 of the cabinet 12.

In use and assuming that the tier of drawers is locked, to unlock them the proper

key is inserted in the lock 22 and the bolt 23 withdrawn from the keeper 24. The top drawer is partly withdrawn and any of the other drawers may then be opened, as 5 the strips 19 are readily swung outward, either by pulling out a drawer or by swinging them out before a drawer is opened. To lock the tier of drawers, the lower ones are closed, the strips 19 are swung back 10 against them and the lock controlled drawer closed and locked. The strips 19 are now positively held in overlapping position, in front of the tier of drawers by the projecting members 21 of the lock controlling 15 drawer 15.

The invention may also be applied to other cabinets, cases or the like, containing a tier of drawers, but it is particularly adapted to withstand the usual rough usage 20 to which trunks are put.

More or less variation of the exact details of construction is possible without departing from the spirit of this invention; I desire, therefore, not to limit myself to 25 the exact form of the construction shown and described, but intend, in the following claims, to point out all of the invention disclosed herein.

I claim as new, and desire to secure by 30 Letters Patent:

1. Means for locking a tier of drawers in a cabinet, one drawer of which is lock controlled, comprising two drawer retaining members hingedly connected to the front 35 of said cabinet and arranged when in operative position to overlap drawers of the tier, and means fixedly connected with the lock controlled drawer engaging with said drawer retaining members and acting to 40 hold said drawer retaining members in op-

erative position overlapping the drawers when said lock controlled drawer is closed.

2. Means for locking a tier of drawers in a cabinet, one drawer of which is lock controlled, comprising two drawer retaining 45 members hingedly secured to the cabinet and arranged when in operative position to overlap drawers of the tier and means fixedly connected with the lock controlled drawer, overlapping said drawer retaining members and acting to hold said drawer retaining members in operative position when said drawer is closed.

3. Means for locking a tier of drawers in a cabinet, one drawer of which is lock controlled, comprising two drawer retaining strips hingedly secured to the cabinet and arranged when in operative position to lock the drawers of the tier, other than the lock controlled drawer, and strip engaging 60 members connected with and projecting from the lock controlled drawer, overlapping said drawer retaining strips and acting to hold said drawer retaining strips in operative position when the said lock controlled drawer is closed.

4. In a wardrobe trunk a combination of a cabinet and a tier of drawers slidably supported therein, one drawer of which is narrower than the others and is lock controlled, 70 two retaining strips hingedly secured to said cabinet and extending past the tier of drawers and arranged to overlap the drawers of the tier other than the lock controlled drawer, strip holding members secured to 75 the lock controlled drawer projecting therefrom and arranged to overlap said retaining strips and thereby hold them in position overlapping said other drawers.

BEN M. HAMLIN.
